ANTI-LOCKING DEVICE FOR REFRIGERATORS

Gaylord B. Kidwell, 5024 34th Road N.,
Arlington 7, Va.

Filed May 4, 1960, Ser. No. 26,922

4 Claims. (Cl. 109—63.5)

(Granted under Title 35, U.S. Code (1952), sec. 266)

The invention described herein, if patented, may be manufactured and used by or for the Government for governmental purposes, without the payment to me of any royalty thereon.

This invention relates to means for preventing the inadvertent closing, sealing, and locking of doors, such as refrigerator doors, so as to prevent accidental loss of life by reason of children becoming locked in abandoned refrigerators or in refrigerators stored in warehouses or the like.

A primary object of the invention consists in the combining with a conventional refrigerator having a hinged door, sealing means between the door and refrigerator body, and a latch for automatically locking the door when moved into cooperative sealing relation with the gasket, of means operable by a screw driver or the like for preventing the door from being completely closed and locked inadvertently.

Other objects and advantages of the invention will be apparent from the following description taken in connection with the accompanying drawings in which,

FIGURE 1 is a front elevational view of a conventional refrigerator in which the present invention is installed, the door being ajar, and showing the anti-locking device in inoperative position;

FIGURE 2 is a sectional view of the structure of FIGURE 1, taken on the line 2—2 of that figure;

FIGURE 3 is a fragmentary sectional view taken on the line 3—3 of FIGURE 2; and

FIGURES 4 and 5 are fragmentary sectional views showing the anti-locking means moved into anti-locking position.

Referring to the drawings in greater detail and by reference numeral, the body of the refrigerator, or other container, which it is intended to be tightly sealed is indicated by the numeral 1, and its closure by the numeral 2. This closure is hinged to the body of the refrigerator or container as indicated by the numeral 3 and is provided with a gasket 4 for cooperating with a sealing recess 5 in the body of the refrigerator so as to tightly close the same against the passage of air into or out of the container. The free edge of the door 2 is provided with a hand-operated latch 6 of any preferred form and adapted to cooperate with a complete latch portion 7 attached to the door jamb to bring the faces of said body portion and of said door into sealing contact with each other. The entire anti-locking attachment comprises a door stop 8 slidably mounted in a recess 9 formed in the door jamb and extending in a direction normal to the plane of the door when the latter is in closed position. Swivelly mounted in the base of the recess 9, as indicated by the numeral 10, is a screw threaded post 11. This member 11 threadedly engages a sleeve 12 which is integral, or otherwise fixed, to the base of the stop member 8. This screw member 11 extends to a point flush with the outer face of the refrigerator and is provided with a kerf 13 adapted to receive the operative end of a screw driver in the usual manner through the face of door stop 8, so that the screw may be rotated in either of two directions.

As heretofore indicated, the purpose of this invention is to prevent accidental loss of life, especially of small children who sometimes climb into abandoned refrigerators, or even new refrigerators stored in a warehouse or the like, and accidentally or otherwise close the door

2

which automatically locks as by the latch indicated (reference numerals 6 and 7) in the present illustrations. Various complicated locking mechanisms have been heretofore provided for permitting the latch of a refrigerator door to be disengaged from the inside of the refrigerator.

For several reasons, such devices are not entirely satisfactory. With the present invention, the accidental death of children in a refrigerator or the like is entirely prevented since it is only necessary that the person discarding the refrigerator, or, in the case of new refrigerators, the custodian thereof, rotate the screw 11 in a clockwise direction so as to partly withdraw the stop 8 from the interior of the recess 9 as indicated in FIG. 4 which will then operate to prevent the complete closure of the door as indicated in the FIG. 5. In the case of a refrigerator which is in use, it is only necessary that the screw be rotated in a direction to completely carry the door stop 8 into the base of the recess 9 so that the door may be closed sufficiently to bring the gasket 4 into cooperative relationship with the recess 5; it is assumed, of course, that a child cannot be confined in a refrigerator in actual use for a sufficient period of time to cause suffocation. It should also be noted that by reason of the requirement of a screw driver or the like to operate the screw so as to permit the door to completely close, it seems obvious that it would be practically impossible for an abandoned refrigerator having the door stop 8 in extended position to be operated by children so as to permit the door to be closed.

In accordance with the patent statutes I have described what I now consider to be the preferred form of the invention but inasmuch as various minor changes may be made in structural details without departing from the spirit of the invention it is intended that all such changes be included within the scope of the appended claims.

I claim:

1. In a refrigerator having a body portion, and a door hinged to said body portion, said body portion and said door having faces adapted to be brought into air-tight sealing contact with each other when said door is closed: a recessed portion in one of said faces, said recessed portion extending normal to the plane of said door when said door is closed, a screw-threaded post rotatably mounted in the rear of said recessed portion and terminating in a plane not extending beyond said last-named face, and a rigid stop member having an internally screw-threaded aperture extending therethrough and threaded on said screw-threaded post, said screw-threaded post being accessible through the face of said stop member, and said stop member being reciprocable in said recessed portion into and out of projecting position by rotating said screw-threaded post; whereby said refrigerator door may be closed only when said stop member is retracted, and whereby accidental closing of said refrigerator door is prevented when said stop member projects from said recessed portion into the path of said door.

2. In a refrigerator having a body portion, and a door hinged to said body portion, said body portion and said door having faces adapted to be brought into air-tight sealing contact with each other when said door is closed: a recessed portion in said face of said body portion, said recessed portion extending normal to the plane of said door when said door is closed, a screw-threaded post rotatably mounted in the rear of said recessed portion and terminating in a plane not extending beyond said last-named face, and a rigid stop member having an internally screw-threaded aperture extending therethrough and threaded on said screw-threaded post, said screw-threaded post being accessible through the face of said stop member, and said stop member being reciprocable in said recessed portion into and out of projecting posi-

tion by rotating said screw-threaded post; whereby said refrigerator door may be closed only when said stop member is retracted, and whereby accidental closing of said refrigerator door is prevented when said stop member projects from said recessed portion into the path of said door.

3. In a refrigerator according to claim 1, a sealing gasket disposed between said door and said body portion, said sealing gasket being clear of said recessed portion and of said reciprocable stop member.

4. In a refrigerator according to claim 1, a sealing gasket disposed between said door and said body portion,

said sealing gasket being clear of said recessed portion and of said reciprocable stop member.

CERTIFICATE OF CORRECTION

Patent No. 3,026,825

March 27, 1962

Gaylord B. Kidwell

It is hereby certified that error appears in the above numbered patent requiring correction and that the said Letters Patent should read as corrected below.

Column 3, line 11, for the claim reference numeral "1" read -- 2 --.

Signed and sealed this 10th day of July 1962.
